UNITED STATES PATENT OFFICE.

ALFRED ERNEST AMES, OF TORONTO, CANADA.

DESIGN FOR A VELOCIPED-SADDLE.

SPECIFICATION forming part of Design No. 28,036, dated December 14, 1897.

Application filed July 23, 1897. Serial No. 645,740. Term of patent 14 years.

To all whom it may concern:

Be it known that I, ALFRED ERNEST AMES, a subject of the Queen of Great Britain, residing at Toronto, in the county of York, in the Province of Ontario, Dominion of Canada, have invented and produced a new and original Design for Velocipede-Saddles, of which the following is a specification, reference being had to the accompanying drawings, forming a part thereof.

This design relates to the configuration of a velocipede-saddle, the distinctive features of which consist of a main or rear portion having forwardly-converging sides and carrying raised seat-pads of corresponding form arranged side by side and a front portion of open or skeleton form which extends from both front ends or points of the main portion forwardly in the form of a U-shaped loop having a depending front end.

In the accompanying drawings, Figure 1 is a perspective view of a velocipede-saddle embodying my design. Fig. 2 is a side elevation, and Fig. 3 a top plan view, thereof.

The frame of the saddle consists of a plate A, which enlarges from its front end toward its rear end and has its rear portion a curved or bent upward. The contour of the frame comprises an inwardly-curved front end b of substantially semicircular shape, forming two forwardly-projecting points b' b' on opposite sides of the frame, two sides c c, which diverge rearwardly from the points b' b', a slightly-curved rear end d, and two outwardly-curved portions d' d', which connect the diverging sides c c with the rear end d. The frame is

provided centrally with a perforation e and around its entire edge with a depending flange f.

G G represent the pads or cushions of the saddle, which are arranged side by side on the frame on opposite sides of its longitudinal center line and which together conform substantially to the shape of the frame and have their rear portions g raised above their front portions g'. In outline each pad has a straight longitudinal inner side g², which is separated from the opposing inner side of the other pad by an intervening space g³, a diverging outer side g⁴, an inwardly-curved front end g⁵, a slightly-curved rear end g⁶, and outwardly-curved portions g⁷ g⁸, connecting the inner and outer sides, respectively, with the rear end.

The front portion or pommel II is of open or skeleton shape, being formed of a bent round rod, and extends from the points b' of the main portion forwardly on converging side lines h to its depending front portion h'. The saddle therefore presents in its front portion an opening which is bounded at the rear by the concave front of the main portion and at the sides and front by the open or skeleton shaped front portion.

I claim as my invention—

The design for a velocipede-saddle, substantially as herein shown and described.

Witness my hand this 14th day of July, 1897.

ALFRED ERNEST AMES.
